PAGE 2

Fig. 1 is a side elevation of a rotary wing aircraft, showing my new design.

Fig. 2 is a front view of the same.

Fig. 3 is a rear view of the same.

Fig. 4 is a plan of the same.

The aircraft is symmetrical, the opposite side being essentially like the side shown in the drawings.

I claim:

The ornamental design for a rotary wing aircraft, as shown and described.
